UNITED STATES PATENT OFFICE.

THOMAS J. MOORE, OF BROOKLYN, NEW YORK, ASSIGNOR TO ESTHER J. MOORE, OF SAME PLACE.

DRAWERS-SUPPORTER.

SPECIFICATION forming part of Letters Patent No. 537,166, dated April 9, 1895.

Application filed November 5, 1894. Serial No. 527,880. (No model.)

To all whom it may concern:

Be it known that I, THOMAS J. MOORE, a citizen of the United States, residing at Brooklyn, in the county of Kings and State of New York, have invented a new and useful Improvement in Drawers-Supporters, of which the following is a specification.

My invention relates to means for supporting undergarments, especially men's drawers.

Usually men's drawers and similar undergarments are supported by straps and spring jaw clamps connected to the front forked ends of the suspenders or similar devices. These clamps are not readily disengaged from the waist band of the drawers or other undergarments and the teeth of the jaws are liable to tear the fabric.

My invention consists in a device for connecting the drawers or other undergarment at the waist band to the pants or other support at the waist band, and comprises a plate of sheet material such as metal with an open center and with holes in pairs by which it is secured by sewing to the inner face of the waist band of the pants or other support. Two of these plates are preferably employed and they are usually located about midway between the pairs of front suspender buttons. The plate is made with horizontal and vertical intersecting openings or slots constituting an open center similar in shape to a quarter-foil, the opposite ends of one slot being preferably narrower than the opposite ends of the other slot, the narrower ends being in use set horizontal. Buttons are sewed to the outer face of the waist-band of the drawers or other undergarment, to coincide with the plates on the waistband of the pants or other article of clothing.

In use the button is tipped to bring its lower edge forward and the button is inserted edge-wise through the horizontal slot in the plate and is simultaneously turned parallel to the fabric of the pants, and the weight of the drawers or undergarment causes the button to move down between the plate and pants so that the shank or attachment of the button finds a seat in the lower end of the vertical opening in the plate. By pressing on the outside of the pants the top edge of the button is tipped back so that it can be lifted out.

In the drawings Figure 1 is an elevation of

the inner face of part of a pants waistband showing a plate and a button in place, and Fig. 2 is a vertical section in larger size. 55

The waistband of the pants is represented by the cloth *a* and connected lining *b*, and the waistband *c* of the drawers is shown of double thickness and to this latter the button *d* is secured by sewing threads or otherwise 60 at *e*.

The plate *f* preferably of metal is provided with several pairs of holes *2* for the sewing threads by which it is secured to the inner face of the pants waistband and preferably 65 midway between the suspender buttons *3* *4*. The plate *f* has an open center preferably of quarter-foil conformation with vertical and horizontal intersecting openings or slots. Usually the opposite horizontal opening *4* is 70 narrower than the other and vertical opening *5*, the plate being sewed to the pants waistband so that the narrower opening is set horizontally. The ends of the openings are preferably rounded. The ends of the opening *5* 75 are adapted to receive the button attachment or conform to the circular button shank and receive the same so that there is little liability of the button shifting and no liability of the sewing threads *e* being cut by coming in 80 contact with the plate *f*.

The size of the opening *4* is sufficient to freely receive the head of the button *d*, and in connecting the drawers to the pants for support the lower edge of the button is tipped 85 forward, and the head is passed edgewise through the horizontal part of the opening and is simultaneously turned into a vertical position and the weight of the drawers causes the button to move down between the plate 90 and the pants so that the circular shank finds a seat in the curved portion *5* of the plate.

Pressure on the outside of the pants tips the top edge of the button back so that it can be lifted out of the plate readily and quickly. 95

My device is exceedingly simple, efficient, and easily applied.

I claim as my invention—

The combination with a circular button having a central shank to be secured to the 100 waistband of the drawers, of a plate of sheet material having holes for sewing threads to secure the same to the inner face of a pants waistband and having horizontal and vertical inter-

seeting slots or openings forming an open center of substantially quarter-foil conformation adapted to receive the button edge-wise through two opposite portions of the opening 5 and to hold the shank in the intermediate portion of the opening, substantially as set forth.

Signed by me this 26th day of October, A. D. 1894.

THOMAS J. MOORE.
